APPARATUS FOR RECOVERING THE HYDRAULIC ENERGY OF A HIGH VELOCITY FLOW OF WATER UNDER FREE SURFACE CONDITIONS

Pierre Francois Danel, Grenoble, France, assignor to Ateliers Neyret-Beylier & Piccard-Pictet, Grenoble, France, a corporation of the French Republic

Application February 19, 1948, Serial No. 9,396
In France October 9, 1946

Section 1, Public Law 690, August 8, 1946,
Patent expires October 9, 1966

7 Claims. (Cl. 61—1)

1

The present invention has for an object to provide a means permitting the transformation of kinetic energy of a high velocity flow of water in an open channel or under free surface conditions into potential energy with a small loss of such energy.

Various procedures are already known for bringing about this transformation or recuperation. The best known is that involving the production of a hydraulic jump. This method, however, has the disadvantage that there is a substantial loss of head.

It has likewise been sought to utilize the kinetic energy of the water to make it go up an opposed slope in such manner as to lead it gradually to the level of recuperation that is desired.

Unfortunately, when the inclination of the bottom of the channel goes up again, the depth of the water increases at the bottom of the slope and the torrential flow slackens while rapidly approaching a condition of critical velocity. Even before this transition there is risk that a hydraulic jump will occur and prevent the phenomenon from taking place. However, useful results are attained in the following manner:

An opposing slope allows the flow to go up again until a certain point beyond which it becomes impossible to go further without bringing about a hydraulic jump. If the bottom is then gradually flattened so as to establish a slightly rounded or sloping sill, the resulting divergence in a vertical plane causes the water to pass along and over this flattened portion or sill without slackening the flow to the point where a condition favorable to hydraulic jump will be created in the area at the bottom or foot of the slope, i. e., the foot of the opposed slope on the upstream side of the sill. Consequently, a good recovery of energy is possible under these conditions. After passing the sill the water level may then go up again to a point adjacent the plane of the head. While this method will insure a satisfactory recovery of the potential energy under ideal conditions, it has the drawback that a stable flow in that part of the channel along and over the rounded sill or crest is difficult to realize in practice.

The present invention has for an object to improve the stability of such recovery systems

5 and, in particular, to utilize to the maximum the principle of the opposed slope in downstream position with respect to the portion of a flume or other channel through which a torrential flow is caused to travel without tending to a hydraulic jump condition.

10 My invention is based on my observation that a flow of water passing at high velocity or under conditions of torrential flow from a downwardly inclined channel or flume on to an opposed upwardly inclined slope, i. e., a channel section inclined upwardly in the direction of the downstream portion of the channel, may be caused to travel upwardly along such opposed slope in a suitable manner without tendency to hydraulic jump by arranging the side walls of the channel in the opposed slope portion thereof so that they gradually diverge in the downstream direction from the bottom end of such opposed slope to the downstream end thereof. The divergence of the side walls should be varied in such manner so as to conserve to the flow its torrential character, i. e., so that the flow velocity is always greater than the wave velocity. As otherwise expressed the Froude number of the flow should 15 always have a clearly defined value greater than one. As in the prior system previously described the opposed slope may be associated with a slightly rounded or sloping sill over which the 20 water is passed from the opposed slope thus insuring the recovery of the remainder of the recoverable energy.

25 The arrangement of my invention whereby diverging side walls are substituted in the opposed sloping portion of the channel for the parallel side walls heretofore used has the advantage of insuring that the water may be delivered in torrential flow to a definitely higher plane than with the use of parallel walls.

30 The recovery on the sloping sill is therefore of less importance than in the prior system, which is a definite advantage for the stability of the flow. The sloping sill may even be suppressed if it is not desired to obtain a maximum recovery.

35 The invention has numerous applications in situations where it is desired to obtain a substantial lowering of the water level while at the same time recovering in potential form the velocity energy by causing the water level to rise up 40 again almost to the initial level.

2

In order to better understand the invention there are given hereinafter several examples of modes of its application supported by the accompanying drawings in which:

Fig. 1 is a view in part longitudinal section and part side elevation of a channel section embodying the invention and introduced into a hydraulic conduit of conventional form;

Fig. 2 is a plan view of the arrangement of Fig. 1;

Fig. 3 is a view in part side elevation and part longitudinal section of another form of water passage utilizing the invention;

Fig. 4 is a half plan view of the channel portion of the structure of Fig. 3;

Figs. 5 and 6 are, respectively, similar views as those of Figs. 3 and 4 showing the application of the invention to a Venturi channel.

Fig. 7 is a part longitudinal section and part side elevation showing the application of the invention to a module and check gate construction of a type employed in distributing irrigation waters.

It is often desirable to obtain the maximum rate of flow through a hydraulic channel, as for example, in emptying drainage basins of a temporary nature such as used in evacuating floods, etc.

The functioning of these canals or conduits leading from drainage basins, whether in open channel or under pressure involves generally the diverting of the flow to the bed of a river and consequently at a point imposed by the water level therein.

The present invention makes it possible to lower the water level in such drainage basins at a relatively high rate and under conditions utilizing a torrential rate of flow even though the difference between the level in the drainage basin and the water level in the river at the point where the waters are diverted to it is relatively small. This is made possible because according to the invention the water may be discharged from the drainage basin at a torrential rate of flow even though the water so discharged has to be elevated again to a level approaching that of the drainage basin in order to effect the discharge into the river at the water level obtained therein. Among other resulting advantages the dams customarily employed for impounding flood waters may be made of diminished height while at the same time effecting the temporary impounding of such flood waters.

In Fig. 1 is shown at 1 the outlet of the drainage channel through which water passes under conditions of torrential flow, at 2 the opposed upwardly inclined slope with divergent walls corresponding to 3 (Fig. 2), at 4 the raised sill or crest and at 5 a downward slope of low incline. The surface of the water follows substantially the line indicated by 2 in Fig. 1 passing through the critical depth in the neighborhood of the crest. It does not produce a hydraulic jump characteristic and the recovery of energy continues on the down slope 5.

For example, one may calculate the divergence of the walls in such a way that the Froude number (V^2/gh) which measures the torrential character (velocity head) of the flow remains constant and clearly more than 1. In these conditions, the depth of the water noticeably decreases in approaching the raised sill or crest 4.

The flow is produced in the way described herein only for a certain range of discharge rates above a certain minimum rate of flow,

This range of discharge rates corresponds well to the case of the evacuation of floods which requires the discharge of large volumes at high rates of discharge. When the rate of discharge diminishes below this limit the flow forms itself into a hydraulic jump with the consequence that the channel abruptly fills up to the level represented in dotted line on Fig. 3 with the result that the discharge outlet 7 becomes submerged.

The rate of discharge then notably diminishes but this condition persists only so long as the rate of discharge remains low. If it tends to increase anew, the hydraulic jump will disappear, and the diverging channel will function again as it did before. In Fig. 3 and the following figures the downward slope that extends beyond the raised crest and permits the further recovery of the energy is not shown, but it will be understood that this slope will ordinarily be provided and in that case it may be the same as that in Fig. 1. On the other hand, when a maximum recovery is not desired, the final downward slope may be omitted and the sill or crest 4 is designed without special precautions with respect to the contour of the succeeding portions of the channel or its mouth. Either of the two arrangements above may be applied in all of the modifications herein described.

Figs. 3 and 4 show the invention applied in a channel provided with a sharply downwardly inclined weir designed to create a torrential flowing of the water from the drainage space or basin. When the velocity head of the water is sufficiently great to insure the torrential flow, the flow takes then the form indicated in full line on Fig. 3.

This disposition may advantageously be utilized in the case of a water take-off passage which is required to function only in periods of low water. The diverting sill is arranged for example in the side wall of a canal. The water take-off is then placed, for example, at 7. It will thus be seen that the water take-off ceases to function when the level upstream is raised to bring about a marked increase in the velocity head. This corresponds to periods of floods and permits the removal of materials such as gravel, pebbles, etc., encumbering the flow at such times without danger that they will pass into or plug the take-off 7, which, for example, may be normally used to conduct irrigation waters to points of distribution. In normal periods the flow establishes itself through the passage 7 due to the filling up of the space 8 following the change to a hydraulic jump condition. The level of the water establishes itself at the level indicated by the dotted line and the water take-off passage 7 discharges normally.

Figs. 5 and 6 show how the invention may be utilized in measuring the volume of the discharge.

It is known that in a given channel the critical depth of the flow is uniquely a function of the discharge. Therefore, the measurement of this depth constitutes a measure of the discharge. This method of measurement has already been used in Venturi channels that present a raised bottom or crest and a narrowing at the point of critical depth. Unfortunately, the energy recovery of standard canals is insufficient and such forms of apparatus remain of little use in spite of their simplicity because of the considerable waste of energy that is produced. The present invention may be applied to this type of measuring apparatus with a minimum loss of energy. The height or critical depth of the water is measured at 9.

Fig. 7 shows an application of the invention in a module or flow controlling device of the type which includes a rounded and downwardly inclined dividing crest or sill surmounted by an adjustable inclined metal plate 19, behind which the water level may rise. The discharge of this type of apparatus is practically constant when the level upstream is held between two designated adjacent points. This apparatus is very useful for maintaining constant the discharge through a water take-off. As heretofore employed a hydraulic jump has been relied on to recover the velocity energy. In cases where large volumes of water are to be discharged, the dimensions of the hydraulic jump become such that an undue waste of energy will occur in most cases if a single apparatus is employed. This is why the apparatus is usually divided into a great number of small distinct modules. This is at the same time a complication and an advantage, for this allows of exact regulation of the discharge at the desired value by opening at will a selected number of sluiceways.

Nevertheless in many cases, it becomes desirable to decrease the number of these sluiceways. The present invention by augmenting the possible recovery of the velocity energy thereby notably improves the functioning of a single module and likewise makes it possible to eliminate a certain number of the installations as compared with the number heretofore considered necessary.

It is also to be understood that the module and check plate of Fig. 7 may be associated with any one whatsoever of the widening channels of opposed slope of other figures of the drawing and in particular in association with that including a take-off passage shown in Fig. 3.

The invention is by no means limited to the specific embodiments described. It is applicable in various other forms that will suggest themselves to one versed in the art who desires to recover the greater part of the energy of a torrential flow.

I claim:

1. An apparatus for recovering the kinetic energy of a torrentially flowing stream of water in the form of potential energy or hydraulic head comprising an open flume receiving such flowing stream and having in the receiving portion thereof an inclination downstream sufficient to insure that the water will travel therealong at a velocity in excess of the critical velocity, and a second flume portion leading from the downstream end of said receiving portion to an elevated point of discharge approximating the height of the bottom of the flume at the entrance thereof, said second portion having confining side walls diverging gradually from one another in the direction toward said point of discharge, the divergence of said walls being within the range where the flow velocity of the water passing therebetween is greater than the wave velocity thereof.

2. An open control flume for normally conducting water from an upstream source of supply to a water take-off conduit and for automatically diverting water away from said take-off during conditions of substantially increased hydraulic head at said upstream source, comprising a downwardly inclined channel leading from said source of supply and merging at its lower end with an oppositely inclined channel constituting a continuation thereof and leading to an elevated point of discharge, said oppositely inclined chan-

nel having confining side walls which diverge gradually from one another in the direction toward said point of discharge, and said flume having an off-take passage in the side wall thereof adjacent the point of merger of said channel portions, said off-take being spaced from the bottom of said channel sufficiently to permit water passing along the channel at a velocity greater than the critical velocity to pass beneath said off-take.

3. An open flume for conducting water from an upstream source of supply to a distant point without large loss of potential head which comprises a rounded sill extending upwardly from the bottom of the flume channel and presenting inclined surfaces respectively facing upstream and downstream therefrom, said inclined surface facing downstream having an inclination sufficient to insure that water passing thereover will maintain a flow velocity in excess of the wave velocity in traveling thereover, and said flume having a second channel portion communicating with and inclined upwardly from the bottom of said downstream facing surface of said sill in the downstream direction, said second channel portion having side walls diverging gradually from one another in the downstream direction at an angle within the range where the flow velocity of the water passing therebetween may be maintained greater than the wave velocity thereof.

4. An apparatus according to claim 3, wherein the side walls of the channel opposite the downstream facing surface of said sill gradually converge in the downstream direction and cooperate with the diverging side walls of the second channel portion to form a Venturi throat in said channel.

5. An apparatus according to claim 1, wherein the downstream inclined flow-receiving portion of said flume is associated at its upper end with a check gate cooperating therewith to control the discharge of water to said flow-receiving portion from an impounded body of water.

6. Apparatus for recovering the kinetic energy of a torrentially flowing stream of water in the form of potential energy, comprising a conduit for discharging such a torrentially flowing stream, a divergent open flume section having its inlet connected to the discharge end of the conduit to receive water therefrom, said open flume section having a bed whose elevation increases gradually in the downstream direction and a sill at its outlet over which the water is discharged, the divergence of said open flume section being so related to the depth as to maintain the velocity of flow greater than the wave velocity throughout said flume section.

7. Apparatus for recovering the kinetic energy of a torrentially flowing stream of water according to claim 6, including a second open flume section connected to said first-mentioned section to receive the discharge therefrom, said second section having a bed whose elevation decreases in the downstream direction.
